UNITED STATES PATENT OFFICE.

HERBERT SAMUEL RAUH, OF NEW YORK, N. Y.

LEGGING.

Application filed December 30, 1926. Serial No. 157,933.

My invention relates to a legging or gaiter. The object of my invention is to modify the usual type of this article of footwear to improve its appearance, make it more convenient to apply to the wearer's foot, and provide certain advantages when so applied. Two forms of my improved gaiter illustrating the invention are shown in the accompanying drawings, in which Fig. 1 is a side elevation of the one form, Fig. 2 a side elevation of the other form, and Fig. 3 a cross-section on the line 3—3 of Fig. 2.

Fig. 1 illustrates my invention as applied to an ordinary buttoned gaiter 1 of the knee length type having the usual buttons 2, button holes 2^a and strap 3. To the upper portion of this gaiter is attached a cuff 4 by means of seam 5. The seam 5 passing, as it does, through the entire upper portion of the gaiter proper 1, sews together at the top the overlapping portions thereof, and it will therefore be necessary, in a gaiter of the particular construction shown in the figure, either to make the upper portion of such gaiter proper large enough to admit the shoe of the wearer when on the wearer's foot, or to make the gaiter proper of material sufficiently elastic so that the opening can be sufficiently enlarged for this purpose.

The cuff 4 is made of elastic material, preferably knitted material, and long enough to permit it to be folded over at least once and pulled down far enough to cover and conceal the seam 5 and, while so doubled, to extend to a distance above such seam sufficiently to perform one or more of the functions or provide one or more of the advantages hereinafter specified. In Fig. 1 my improved gaiter is shown in a condition in which the seam 5 is exposed to view, but when the article is worn this seam is not to be so exposed. The proper arrangement of this cuff, when in use, is shown in side elevation in Fig. 2 and in cross-section in Fig. 3.

The form of my gaiter shown in Fig. 2 is in all respects similar to the one shown in Fig. 1 except that the closure of the gaiter, after it has been placed upon the foot, is effected by a slide fastener 6, consisting of the usual stringers and slider, which may be of any of the known types now on the market, and the strap 7 is shown as made of elastic material. I have provided the slider (not shown) of the slide fastener with a metal loop 8 through which passes a strap 9 provided with snap fastener heads 10 en-

gaging with snap fastener bases (not shown) applied in the usual manner to the body of the gaiter. When the gaiter of Fig. 2 is in use, the loop, strap and fasteners are in the 60 position shown in the drawing. When it is desired to open the gaiter to remove it from the foot, the slide fastener heads 10 are pulled out of engagement with their respective bases and the strap 9 is then folded outwardly and used as a convenient means for exerting pull upon the slider through the medium of the metal loop 8.

When the gaiter, of either form shown in the drawings, is to be applied to the foot, it 70 is opened and the cuff 4 preferably pulled downwardly around the body 1 of the gaiter so as to avoid its catching on parts of the shoe. The shoe is then inserted through the upper portion of the gaiter body and the 75 gaiter pulled up until the strap 3 or strap 7 contacts with the instep. The cuff 4 is then placed into the position shown in Fig. 1 or Fig. 2 or may, if desired, be pulled up as far as it will go without leaving any horizontal 80 fold therein. The cuff, when placed in any one of the preliminary positions just described, will hold the gaiter in place upon the wearer's leg with sufficient firmness to permit the application of the article to be 85 interrupted without loss of adjustment and, in the case of the buttoned gaiter, to permit the buttoning operation without the necessity of holding the gaiter in place with one hand, while the buttoning is done with the 90 other.

The final adjustment of the cuff is made after the gaiter has been securely fastened to the wearer's foot. In order to conceal the connection between the cuff and the gaiter 95 proper the upper portion of the cuff should be pulled down sufficiently to conceal the seam 5, but otherwise the adjustment may be such as the wearer's fancy may dictate and the length of the cuff permit. At any rate, 100 the cuff permits the structure to be readily adjusted as to height and will serve to protect the leg against cold. The cuff will conceal any gap which may exist between the upper edge of the gaiter proper and the wearer's leg and thus will not only improve the appearance of the article but will make it possible for the manufacturer to supply his trade with a lesser number of sizes. In very cold weather, or under very muddy street 110 conditions, the cuff may be pulled up as far as it will go, thus affording additional pro-

tection to the leg or stocking of the wearer. I claim:

5 A close fitting knee length legging comprising a body portion having an opening at one side extending upwardly from the bottom edge and terminating adjacent the upper edge of the body, said opening being defined by edge portions, fastening means for

detachably uniting said edge portions, and an endless elastic cuff attached to the upper ¹⁰ edge of the body adapted to fit about the leg of the wearer above the calf and adjust itself to the contour thereof.

In testimony whereof I have hereunto set my hand.

HERBERT SAMUEL RAUH.
